CLAIM

The ornamental design for a packaging box, as shown and described.

DESCRIPTION

FIG. 1 is an upper perspective view of the packaging box showing my design in a closed position;

FIG. 2 is another upper perspective view thereof in a partially closed position;

FIG. 3 is a top plan view of the packaging box in the partially closed position of FIG. 2;

FIG. 4 is still another upper perspective view thereof in an opened position;

FIG. 5 is a side elevation view of the packaging box in the opened position of FIG. 4;

FIG. 6 is a front elevation view of the packaging box in the opened position of FIG. 4; and,

FIG. 7 is a top plan view of the packaging box in a fully opened position.

No claim is made to features beyond the views presented.
